(57) **CLAIM**

The ornamental design for a video unit with integrated features, as shown and described.

DESCRIPTION

FIG. 1 is a top perspective view showing a video unit with integrated features showing our new design;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof; and,

FIG. 8 is a rear perspective view thereof.

The broken lines of the preceding Figures illustrate a boundary and, further, the broken lines are for illustration only and form no part of the claimed design.
